UNITED STATES PATENT OFFICE

FRANK POWYSZYNKI, OF CHICAGO, ILLINOIS

SHOE HEEL CLAMP

Application filed August 31, 1931. Serial No. 560,295.

The present invention relates to shoe heel clamps and has main application in connection with wooden heels, in women's shoes, the object being to retain the wooden heel while the leather layer is nailed thereto to prevent splitting of the wooden heel during the process of driving nails therein.

A further object of the present invention is the provision of a clamp the jaws of which may snugly fit the periphery of the heel and squeeze the same while nails are driven for attaching a layer of leather to the heel for preventing splitting of the heel during the process of driving nails thereto.

Another object of the present invention is the provision of a clamp of the character indicated which may be constructed of comparatively few parts, which may be easily assembled or replaced.

With the above general objects in view and other that will appear as the nature of the invention is better understood the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views,

Fig. 1 is a top plan elevational view of the device, partly in section, showing its operative position upon the shoe heel;

Fig. 2 is a side elevational view of the clamp, partly in section, while the same is in an operative position upon the shoe heel; and

Fig. 3 is an edge elevational view of the spring with the jaws or clamping members at its ends.

Referring in detail to the present drawing the invention includes a pair of L-shaped frame members 10, pivotally hinged by their leg portions by pin 11, in a manner whereby said L-shaped frame members 10 effect a U-shaped frame, as clearly seen on Fig. 1.

The side portions of each of said L-shaped member 10, adjacent the free end thereof is provided with apertures 12, which remain in substantial alinement in both of said sides.

Said apertures are adapted to receive bolt 13, which, at one of its ends, is provided with head 14 while the other end is threaded as at 15 for receiving thereon wing nut 16. Said apertures 12 are slightly larger than the periphery of bolt 13 for permitting play of said bolt 13 within said apertures 12 during the angular shifting movement of the two L-shaped frame members 10 upon pivot 11 at the time pressure is exerted upon sides of said L-shaped members 10 by screwing on the wing nut 16 upon bolt 13. Apertures 12 adjacent head 14 may preferably be square to accommodate therewithin square base 17 of bolt 13, by virtue of which arrangement bolt 13 may remain stationary at the time wing nut 16 is operated.

At the free termination of each side of L-shaped frame member 10, and on the inner face thereof, bores 18 are made for the purpose which will be hereinafter described.

The invention further includes an oblong strip 19 of springy resilient nature made of metal similar to that employed in clock-spring. Said strip 19 is adapted to assume a U-shaped formation while the same is in an operative position within frame members 10 as clearly seen on Fig. 1. Rigidly mounted by soldering or by any other suitable means affixed to said spring strip 19, at the ends and upon the same face thereof are clamping jaw members 20, which at their free faces are suitably grooved as at 21 in order that they may snugly fit the peripheral side of the heel 22 when the device is in an operative position thereupon as clearly seen on Fig. 1.

Said clamping jaw members 20 may be lined by felt or leather lining 23 so as to prevent injury to the heel when the clamping jaw members 20 come in contact therewith.

Spring strip 19 at the opposite face thereof and at each end is provided with relatively short swivel pins 24 which are adapted to be received by their outer free ends within bores 18. Said pins 24 may either be integrally formed with clamping jaw members 20, in which event the same may extend through suitable apertures formed in spring strip 19, or else may directly be affixed to said spring strip 19 in any suitable manner.

From the hereinabove description it will be seen that the clamp is adjustable to suit various widths of heels. By virtue of the fact that strip 19 is of resilient nature easy shifting of clamping jaw members 20 on longitudinal plane with the free ends of L-shaped clamping members 10 is obtained. The swivel arrangement of said clamping jaw members 20 by virtue of bores 18 and pins 24, 5 facilitates ready adjustment of said clamping jaw members 20 to proper position with respect to the adjacent portions of the periphery of the heel at the time pressure is exerted at L-shaped frame members 10 by means of bolt 13 and wing nut 16. Further, by virtue of swivel arrangement of pins 24 at bores 18, the shifting movement of clamping jaw members 20, whereby they seek most natural position with relation to the periphery of the shoe heel at the time pressure is exerted at L-shaped frame members 10, by 10 operating wing nut 16, is facilitated.

From the hereinabove description of the construction and operation of the device it 25 will be seen that when the device is in an operative position upon shoe heel 22, great amount of pressure may be had thereupon by said clamping jaw members, and while this pressure is continued, leather layer 25 may 30 then be safely nailed to the wooden portion of the shoe heel without fear that the heel may split as is a frequent occurrence without the aid of suitable clamping device.

Due to the tendency of strip 19 to open 35 and to assume normal position shown on Fig. 3 on outward angular shifting of the L-shaped frame members 10, on unscrewing of the wing nut 16, pins 24 continue to remain within their respective bores 18, they 40 being forced to remain in that position by virtue of the resiliency of strip 19 and by virtue of its tendency to spread out in order to assume normal position shown on Fig. 3. It is also observed that diameters of bores 45 18 are larger than the diameters of pins 24 permitting swivelling of said pins 24 to considerable degree in order that clamping jaw members 20 may fit various sizes of shoe heels, and further that they may quickly find 50 the most suited position with respect to the heel during the process of tightening of the clamp by screwing on wing nut 16.

While there is described herein a preferred embodiment of the present invention, it is 55 nevertheless to be understood that minor changes may be made therein without departing from the spirit and scope of the invention as claimed.

What I claim as new is:

60 1. A device of the class described comprising a pair of frame members pivotally connected at one of their ends, clamping members, swivel connections between said clamping members and the opposite free ends of said frame members, a bolt passing

through said frame members, a nut upon said bolt for maintaining said frame members in a relative angular adjustment, and a spring device connecting said clamping members for maintaining the same in operative position with respect to said frame members. 65

2. A device of the class described comprising a pair of L-shaped frame members pivotally connected at their leg portions to define a substantially U-shaped frame, the free ends of said frame members being in substantially parallel relation, clamping members swivelingly positioned upon the inner opposed faces of the free ends of said frame members, means for angularly adjusting said frame members, and yieldable means for maintaining said clamping members in operative position with respect to said frame members, said last named means permitting shifting of said clamping members on operation of said first named means in all directions other than transverse with respect to the free ends of said frame members. 70 75 80 85

90 95 100 105 110 115 120 125 130

3. A device of the class described comprising a pair of frame members pivotally connected by one of their ends, clamping members swivelingly positioned upon the other ends of said frame members, means for pivotally adjusting said frame members, and yieldable means for maintaining said clamping members in operative position with respect to said frame members, said last named means permitting shifting of said clamping members on operation of said first named means in all directions other than transverse with respect to said frame members.

In testimony whereof I affix my signature.

FRANK POWYSZYNSKI.
